UNITED STATES PATENT OFFICE

2,399,507

COMBUSTION ENGINE

Fernando G. Prieto, Los Angeles, Calif.

Application February 26, 1945, Serial No. 579,705

3 Claims. (Cl. 123—51)

The invention relates to improvements in combustion engine, having two opposite pistons in every cylinder which will be closed at two ends, and the objects of the improvements are: first, to obtain more power output from the engine with a given amount of fuel; second, to save weight and cost in the manufacture of the engine; third, in some of its forms, to prevent loss of fresh fuel; fourth, to get the burnt gases definitively expelled; and fifth, to cool with fresh air alternatively a part of the cylinders.

Other objects of my invention will be apparent from the disclosures in the accompanying drawing and following specification.

Some forms of the invention are shown in the accompanying diagrammatical drawing.

Fig. 1 is a plan sectional view of a unit in an internal combustion engine of the two-stroke cycle type embodying the invention.

Fig. 2 is a similar view in lesser detail, of an alternate form of the invention.

Fig. 3 is a plan sectional view of a single cylinder of an internal combustion engine of the radial two-stroke cycle type.

Referring to the drawing in greater detail and with more particular reference to Fig. 1, the engine comprises, generally, parallel and closed ended cylinders 5 and 6, the cylinder 5 being provided with working pistons 7 and 8 and with a free piston 9 therebetween, and the cylinder 6 being similarly provided with working pistons 10 and 11 and a free piston 12. The engine further comprises a crankshaft 13; means operatively connecting the crankshaft and the working pistons 7 and 10 comprising connecting rods 14 and 15; similar means operatively connecting the crankshaft and the working piston 8 and 11 comprising connecting rods 16 and 17; an inward-opening valve 18 in each of the working pistons 7, 8, 10 and 11 for allowing the fuel charge to pass through said pistons during the out-stroke when the pressure of said fuel charge is greater than atmosphere, said valves 18 remaining closed during the in-stroke; a fuel line 19 reaching each end of the cylinders 5 and 6 for admitting fuel into said cylinders through back-pressure valves 20a; a valve 20 for controlling the flow of air and of fuel to said cylinders; exhaust valves 21 in each cylinder for discharging the burnt gases therein after ignition of a charge of fuel; and various means and connections completing the engine structure.

The arrangement of the engine is such that the pistons 7 and 10 are directly connected to the connecting rods 14 and 15 by piston rods 22 and 23

respectively. However, the pistons 8 and 11 are connected to the connecting rods 16 and 17 by respective piston rods 24 and 25 which are each formed with a return bend to comprise U-shaped members, as shown. By means of this arrangement, a single crankshaft serves to receive the thrust of the four pistons 7, 8, 10 and 11.

Each valve 18 is placed in a hole or passage 26 in each piston 7, 8, 10 and 11. Said passage 10 extending through each piston from face to face thereof.

The four fuel lines 19 and the four valves 20 are so arranged relatively and respectively as to control the admission to the cylinders 5 and 6 of air or fuel as the case may be. The relationship of the valves 20 to the fuel lines 19 may vary physically and the instrumentalities may vary in design and arrangement with the end in view, however, that the relationship permit 20 the admission of air or fuel selectively and alternately.

The structure of Fig. 2 is similar to that of Fig. 1 with the exception that the connections between the crankshaft 13 and the working 25 pistons 8 and 11 have been modified. The modification entails an inertia member 30 interposed between said crankshaft and each working pistons 8 and 11, as shown, said inertia member being able to deliver power.

30 The valves 20 and 21, in the usual manner, may be moved by a camshaft operatively connected to the crankshaft, or may be driven by an outside mechanism timed in proper synchronization with the operation of the engine.

35 The operation of the engine is as follows:

During the in-stroke of piston 7, air was drawn into the cylinder 5, and during the in-stroke of piston 8, a fuel charge was drawn into said cylinder. Said pistons having finished their 40 in-stroke, a combustion chamber is formed between piston 7 and the free piston 9. At that moment the fuel in the chamber C is ignited by suitable spark plugs, or other firing means (not shown). The resulting gas expansion causes 45 the out-stroke to begin, the pistons 7 and 8 moving outwardly and oppositely with the same velocity. The piston 7 receives its moving force directly from the expanding gases, and piston 8 is moved by the free piston 9 which similarly 50 is impelled by the exploding and expanding fuel charge. During the following out-stroke, the position of the inlet and exhaust valves remain unchanged. Consequently piston 7 expels through valve 20 the air previously entered 55 through the same valve during the in-stroke, thus

cooling the cylinder, and piston 8, while compressing the fuel charge previously entered through the valve 20, closes the back pressure valve 20a in the fuel line 19, and allows said fuel charge to pass through its valve 18 into the space between itself and the free piston 9. It follows then that the free piston 9, instead of following the out-stroke movement of piston 8, gradually slows up and reverses its movement toward piston 7, impelled by the incoming fuel charge through piston 8. At the end of this out-stroke, the inlet and exhaust valves change their position. Now the pistons 7 and 8 begin their in-stroke during which the free piston 9 finally comes in contact with piston 7 thus the burnt gases being totally expelled through the exhaust valve 21 and the fuel charge between piston 8 and the free piston 9 being compressed to form a combustion chamber therebetween. Upon ignition of the fuel charge, the operation above is repeated except that, this time, during the in-stroke of piston 7 a fuel charge will be drawn into the cylinder, and during the in-stroke of piston 8 air will be drawn into said cylinder. The exhaust valves 21 are operated in timed relation to the operation of the engine. One of the exhaust valves 21 is closed when the incoming fuel charge is compressed and exploded, and the other is opened when the burned gases are expelled. The valves are thus alternately operated as can be well understood.

The engine is arranged so that the operation in cylinder 5 is opposite to that in cylinder 6 to effect a balancing of the forces in the engine. Therefore, the pistons in the two cylinders move oppositely with respect to each other.

Only the essentials of the engine of my invention have been disclosed, and it is obvious that skilled persons can readily incorporate such other attending instrumentalities as may be needed to complete the structure. Further, many

changes in the construction as disclosed may be made without departing from the spirit and scope of the invention as claimed. I, therefore, desire to reserve to myself such modification that may fall within the scope of the appended claims.

I claim:

1. An internal combustion engine comprising a crankshaft, parallel cylinders associated with the crankshaft, a pair of opposed working pistons 10 in each cylinder, a freely movable piston between each pair of working pistons to form a combustion chamber between itself and its related working pistons alternately, means directly connecting one working piston of each pair to the crankshaft, and means comprising U-shaped members connecting the other working piston of each pair to said crankshaft.
2. An internal combustion engine comprising a crankshaft, parallel cylinders associated with the crankshaft, a pair of opposed working pistons 20 in each cylinder, a freely movable piston between each pair of working pistons to form a combustion chamber between itself and its related working pistons alternately, means directly connecting one working piston of each pair to the crankshaft, and means including an inertia member connecting the other working piston of each pair to said crankshaft.
3. An internal combustion engine of the radial type, comprising a two-throw crankshaft, a plurality of cylinders, a pair of opposed working pistons 30 in each cylinder, a freely movable piston between each pair of working pistons to form a combustion chamber between itself and its related working pistons alternately; means directly connecting one working piston of each pair to said two-throw crankshaft and means comprising a U-shaped member connecting the other working piston of each pair to said crankshaft.

40

FERNANDO G. PRIETO.
